UNITED STATES PATENT OFFICE.

JAMES W. TILLEY, OF BOSTON, MASSACHUSETTS.

FOOT-REST.

SPECIFICATION forming part of Letters Patent No. 366,437, dated July 12, 1887.

Application filed February 25, 1886. Serial No. 193,238. (No model.)

To all whom it may concern:

Be it known that I, JAMES WILLIAM TILLEY, of Boston, in the county of Suffolk and State of Massachusetts, have invented a new and useful Improvement in Foot-Rests, of which the following is a specification, reference being had to the annexed drawings, forming a part thereof, in which—

Figure 1 is a side elevation. Fig. 2 is an end elevation, with parts broken away to show the internal construction. Fig. 3 is an end elevation showing the foot-rest adjustable as to height, and representing the different positions of the foot-rest in dotted lines. Fig. 4 is an end elevation showing the cover of the hollow top open.

Similar letters of reference indicate corresponding parts in the different figures of the drawings.

The object of my invention is to provide a foot-rest to be used by the occupant of a rocking-chair, the foot-rest being arranged to oscillate, to follow the movements of the rocker.

My invention consists in the peculiar construction and arrangement of parts, all as hereinafter fully described, and pointed out in the claims.

The base A is formed of end pieces, a, connected by rods b b'. In the end pieces, a, are formed mortises c, in which are pivoted the lower ends of the uprights d, upon the upper rod, b'. The uprights d are each provided with a tenon, e, which extends nearly to the bottom of the mortise, and upon opposite sides 35 of the tenon e are placed rubber springs f, which tend to hold the tenon e in a central position, and thus maintain the uprights d normally in a vertical position.

The top B of the foot-rest is of the usual construction, and is secured directly to the upper ends of the uprights d, as shown in Figs. 1 and 2, or it is connected with slotted pieces g, which are adjustably connected with the uprights, and secured by transverse bolts passing through the slotted pieces g and the uprights, as shown in Fig. 3.

The feet of the user are placed upon the cushion or top B of the foot-rest; and while rocking the uprights d swing back and forth upon their pivots, permitting the cushion of the

foot-rest to follow the movements of the rocker, as indicated by the dotted lines in Fig. 3.

In the construction of my improved foot-rest I prefer to employ rubber springs f, arranged as indicated in Fig. 2 of the drawings; but I 55 may employ other forms of springs, placed in other positions, the pivots of the standards being raised, and the lower ends of the standards being weighted.

I make the top B of the foot-rest hollow, and 60 arrange it to open with a hinge, as shown in Fig. 4, to form a receptacle for slippers, brushes, and other articles.

I am aware that a foot-rest supported by telescopic legs pivoted between jaws on the 65 base and to the under side of the foot-rest, the said top and legs being held at any desired inclination by means of curved rods and thumbscrews, is old; and I am also aware that a frame of a rocking and revolving chair has been provided with standards pivoted at their lower ends and held in a vertical position by spiral springs on a rod on opposite sides of a strap projecting from said frame; and I am further aware that rocking foot-stools are old, and I 75 therefore do not claim such inventions.

Having thus described my invention, what I claim as new, and desire to secure by Letters Patent, is—

1. In a foot-rest, the combination, with a 80 base provided with sockets in its end pieces, of uprights pivoted in the said sockets, the top B, secured to the upper ends of the uprights, and springs arranged in the sockets and engaging the uprights for holding them normally 85 in a vertical position, substantially as herein shown and described.

2. In a foot-rest, the combination, with the base A, provided with the mortises c, of the uprights d, pivoted in the said mortises and 90 provided with the tenons e, the springs f in the mortises on opposite sides of the tenons, and the top B, secured to the upper ends of the uprights, substantially as herein shown and described.

JAMES W. TILLEY.
